(57) CLAIM

The ornamental design for a beverage shaker, as shown and described.

DESCRIPTION

FIG. 1 is a perspective view showing the top, front and left side of the beverage shaker showing my new design.

FIG. 2 is a front view thereof.

FIG. 3 is a top view thereof.

FIG. 4 is a left side view thereof.

FIG. 5 is a right side view thereof.

FIG. 6 is a back view thereof.

FIG. 7 is a bottom view thereof; and,

FIG. 8 is a perspective view thereof showing the unclaimed cap in open position.

The broken lines of the cap in the drawings are included for the purpose of illustration and form no part of the claimed design.
